(57) **CLAIM**

The ornamental design for a panel with cut and aligned stick interlayer, as shown and described.

DESCRIPTION

FIG. 1 is a front view of a panel with cut and aligned stick interlayer, shown used in a partition structure;

FIG. 2 is an enlarged front perspective view;

FIG. 3 is a top plan view taken along line 3-3 of FIG. 5;

FIG. 4 is a left side elevation view taken along line 4-4 of FIG. 5;

FIG. 5 is an enlarged front elevation view;

FIG. 6 is a right side elevation view taken along line 6-6 of FIG. 5; and,

FIG. 7 is a bottom plan view taken along line 7-7 of FIG. 5. The broken lines showing environment in the drawings are included for illustrative purposes only and form no part of the claimed design. The outer broken line boundaries in Figures depicting the boundaries of the claimed design indicate that a specific length, width, and thickness form no part of the claimed design and are for illustrative purposes only.
